WINDOW SCREEN

Linwood P. Wright, Falmouth, Maine

Application November 7, 1945, Serial No. 627,220

9 Claims. (Cl. 160—371)

1

My present invention relates to improvements in window screens of that type having a screen element consisting of top and bottom members and a sheet of flexible screening connected thereto which can be rolled for handling or storage and installed from the room interior by means attached to the window casing.

The potential advantage of screens of this type have long been recognized, but structures previously proposed have not permitted those advantages to be realized. This was due to such factors as appearance and the difficulty of having the screening fit tightly against the margins of the area to be screened.

In accordance with my invention, I provide a window screen having side members to be attached to sides of the window casing. Each of the side members consists of a portion to be attached to the window casing, a flange extending into the area to be screened and a cover portion hinged to the first named portion to swing from an open position into a closed position in which it is substantially in engagement with the flange. Attached to each cover portion is a trip and preferably the cover and first named portions are connected by means by which the cover is resiliently held in either its open or closed positions against accidental movement.

A screening element in accordance with my invention consists of a top member adapted to be detachably supported by the upper ends of the flanges of the side members, a bottom member adapted to be detachably connected to the window sill, and flexible screening connected to the top and bottom members and dimensioned to engage with the flanges of the side members.

With a window screen in accordance with my invention, the side members are first attached to the window casing and the screening element may then be readily installed from within the room by first mounting its top members on the flanges with the screening and bottom members on the outside of the flanges. Then, with the cover portions of the side members open, the bottom member is drawn inwardly and attached to the sill with the marginal portions of the screening in contact with the flanges.

In accordance with my invention, the cover portions, when in their open position, are spaced to accommodate the width of the screening and the trips with which each of the cover portions is provided are disposed so that, when the cover portions are in their open position, marginal portions of the screening engage therewith. The positioning of the bottom member of the screen

2

element for attachment to the window sill accordingly causes the screening to engage with the trips and to move the cover portions from their open to their closed position. Preferably the first named and cover portions of the side members are interconnected by means resiliently holding the cover portions in either their open or their closed positions.

Window screens in accordance with my invention have the advantage that ease of installation and effective screening are combined. Additional features are that my window screen may be economically manufactured to be attractive in appearance and in the accompanying drawings I have shown an illustrative embodiment of my invention from which these and its other novel features and advantages will be readily apparent.

In the drawings:

Fig. 1 shows an installed window screen in accordance with my invention as viewed from the exterior of the building.

Fig. 2 is a fragmentary view showing, in perspective, the construction of the side members and the relation of the top member of the screen element thereto.

Figs. 3, 4, and 5 are fragmentary sections as viewed, respectively, along the lines 3—3, 4—4, and 5—5 of Fig. 1.

Fig. 6 shows a connection by which the cover portion of a side member is resiliently held in either its closed or its open position, Fig. 7 is a transverse section on an enlarged scale with side members closed against the screen and the bottom member locked to the sill, and Fig. 8 is a fragmentary section showing a side member in its open position and the bottom member unlocked.

In the drawings I have shown my invention as embodied in a window screen particularly adapted for use in screening the lower half of a double hung window, the upper half of which is indicated generally at 10 in Fig. 1. The sides of the window casing 11, the window sill 12, and the bottom rail 13 of the upper sash (see Fig. 3) define the area to be screened.

In accordance with my invention, I provide side members generally indicated at 14. Each side member 14 comprises a portion 15 adapted to be attached to the casing 11 and having a flange 16 which extends outwardly into the area to be screened substantially in a plane inclusive of the outer face of the rail 13 as shown in Fig. 3.

A cover 17 is connected by hinges 18 to the portion 15 adjacent its edge that is opposite the flange 16 to swing from its open position shown

in Figs. 2 and 6 to a closed position in which it is substantially in engagement with the flange 16 as shown in Fig. 4. In its closed position, the cover 17 defines an acute angle with the portion 15 so that it is inclined inwardly and defines with the portion 15 and the flange 16 a compartment 19, see Fig. 4.

Each of the covers 17 has a trip 20 preferably having a flange 21. When the covers 17 are in their open position, they are spaced apart a distance substantially equal to the width of the area to be screened and in this position each trip 20 projects into that area as shown in Fig. 2. When the covers are in their closed position, the trips 20 are concealed within the compartment 15.

Preferably, I employ means indicated generally at 22 to hold resiliently each cover 17 open or closed to prevent its accidental movement from either position. As may be seen from Figs. 2 and 6, the spring means 22 may comprise a loop 23 of resilient stock fast to the portion 15 of the side member 14 and a loop 24 secured to the cover 17. I interconnect the loops 23 and 24 by a substantially U-shaped wire connector 25 secured at its ends to an eccentric 26 in the loop 23. By this construction, as a cover is swung, the eccentric 26 turns within the loop 23 and tends to wedge it apart. Because of the resiliency of the stock from which it is made, the loop 23 snaps the eccentric from a dead center position into either a position in which the cover 17 is open or closed.

The screen element in accordance with my invention comprises a top member generally indicated at 27, a bottom member generally indicated at 28 and any suitable screening 29 connected at its top and bottom to the members 27 and 28 respectively and dimensioned as required by the size of the area to be screened so that its margins will engage with the flanges 16.

As may be most clearly seen in Figs. 2 and 3, the top member 27 has an inner flange 30 and an outer flange 31 so disposed relative thereto that when the top member 27 is supported by the upper ends of the flanges 16 with the inner flange 30 between them and the rail 13, the outer flange 31 extends downwardly and inwardly so that its edge is beyond the edge of the flange 30 and is in a plane substantially inclusive of the flanges 16. The screening 29 is connected as at 32 to the edge of the outer flange 31. I have shown the upper ends of the flanges 16 as being offset at 33 to accommodate the inner flange 30.

The bottom member 28 is apertured to receive any suitable fastening means such as is indicated at 34. These are attached to the window sill 12 and may be formed as at 35 to receive, for example, the hook 36 with which pivotable knobs 37 on the bottom member 28 are provided thereby to establish means for detachably locking the bottom member to the sill 12.

The bottom member 28 has a flange 38 so disposed that when the bottom member 28 is locked to the sill, the flange 38 extends upwardly and inwardly with its edge substantially in the plane defined by the flanges 16 of the side members 14. The bottom edge of the screening 29 is attached to the edge of the flange 38 as at 39.

Preferably, the width and inclination of the flange 31 of the top member 27 and the flange 38 of the bottom member 28, when such members are installed, are the same as that defined by the covers 17 when in their closed position. The ends of the top and bottom members abut

respectively with the upper and lower ends of the covers 17 when closed and are complementally so formed that the effect of a unitary screen frame is established as will be apparent from Fig. 1. The side, top and bottom members may be made of relatively thin stock formed with strengthening bends which may impart to them an attractive design.

Window screens in accordance with my invention are easy to install and remove. The side members 14 are first attached to the sides of the window casing 11. The window screen element comprising the top and bottom members 27 and 28 and the screening 29 connected thereto, may then be installed from the inside of the room when the covers 17 of the side members 14 are in their open position. This may be readily effected by supporting the top member 27 on the upper ends 33 of the flanges 16 with the inner flange 30 between them and the rail 13, with the screening 29 and the bottom member 28 on the outer side of the flanges 16 and beyond the trips 20.

The means by which the bottom member 28 is attached to the sill are initially positioned so that the screening 29 must be pulled taut before the locking of the bottom member to the sill may be completed. In doing this, the bottom member is drawn inwardly and pulled downwardly over the fastening means 34 and, in so doing, the margins of the screening 29 are brought into contact with the trips 20 thereby causing the screening 29 to close the covers 17 as the bottom member is positioned for attachment to the sill 11. The relation of the screening 29 to the trip 20, the flange 16, and the cover 17 is clearly shown in Fig. 4.

The screening units may be readily removed from the interior of the room when the lower half of the window is raised by turning the knobs 37 to effect disengagement of the bottom member 28 from the sill 11. As the screening 29 is urged outwardly, the covers 17 are opened and the top member 27 is then lifted from the ends 33 of the flanges 16. The covers then are manually closed and the side members remain available for use when it is desired to reinstall the screening unit. The removed screening unit may be rolled up for ease in handling and to permit compact storage.

Many other advantages of my invention will be apparent. Among these may be noted that my invention enables window screens to be readily fitted to houses where the window casings are not properly rectangular. This results from the fact that the flanges 16 are proportioned so that more or less of the screening engages therewith and since there are no side members permanently attached to the screening 29, it may be readily trimmed if desired.

What I therefore claim and desire to secure by Letters Patent is:

1. A window screen comprising a pair of side members, each of said side members including a portion to be attached to a side of the window casing, a flange extending into the area to be screened and a cover portion hinged to said first named portion to swing from an open position to a closed position in which it is substantially in engagement with said flange, and a removable screen element comprising top and bottom members and a sheet of flexible screening connected to said members, said top member detachably interlocking with the upper ends of said flanges, means detachably locking said bottom member

to the window sill, the marginal portions of said screen element engaging said flanges when said top and bottom members are attached respectively to said flanges and to said sill and being held engaged therewith by said cover portions when in their closed position.

2. A window screen comprising a pair of side members, each of said side members including a portion to be attached to a side of the window casing, a flange extending into the area to be screened, and a cover portion hinged to said first named portion to swing from an open position to a closed position in which it is substantially in engagement with said flange and defines an acute angle with said first named portion, and a removable screen element comprising top and bottom members and a sheet of flexible screening, said top member having a web portion and inner and outer flanges, said outer flange tapering inwardly towards said inner flange, said top member being disposed over the ends of the flanges of said side member with the inner flange in engagement with the inner surface thereof, said outer flange having the same inclination as said cover portions in their closed positions and having its edge substantially in the plane defined by said flanges of said side members, said screening being connected to the edge of said outer flange, said bottom member having a portion to be attached to the window sill and a flange extending at the same inclination as said cover portions in their closed positions and having its edge substantially in the plane defined by said side member flanges, and said screen element being attached to the edge of said bottom member flange and having its margins engaged with said side member flanges and being held thereagainst by said cover portions when in their closed position.

3. The window screen of claim 2 in which the ends of the flanges of the top and bottom members engage respectively with the top and bottom ends of the side member flanges and all of said ends are uniformly inclined.

4. The window screen of claim 2 in which the upper ends of the side member flanges are outwardly offset a distance substantially equal to the thickness of the inner flange of the top member.

5. A window screen comprising a pair of side members, each of said side members including a portion to be attached to a side of the window casing, a flange extending into the area to be screened, a cover portion hinged to said first named portion to swing between a closed position in which its edge is substantially in engagement with said flange and an open position, and a trip carried by said cover portions, and a removable screen element comprising top and bottom members and a sheet of flexible screening connected to said members, said top member detachably interlocking with the upper ends of said flanges, means to detachably lock said bottom member to the window sill, said screen engaging said flanges, said covers, when in their open position, being spaced apart a distance accommodating the width

of said screening and exposing said trips in the path of the margins of the screen element.

6. A window screen comprising a pair of side members, each of said side members including a portion to be attached to a side of the window casing, a flange extending into the area to be screened, a cover portion hinged to said first named portion to swing between a closed position in which its edge is substantially in engagement with said flange and an open position, means resiliently holding said cover portion in either of said positions and a trip carried by said cover portions, and a removable screen element comprising top and bottom members and a sheet of flexible screening connected to said members, said top member detachably interlocking with the upper ends of said flanges, means detachably locking said bottom member to the window sill, said screen engaging said flanges, said covers, when both in their open position, being spaced apart a distance accommodating the width of said screening and exposing said trips for engagement by the margins of said screen element and said bottom member is swung inwardly into position for attachment to said sill thereby to close said covers against said flanges.

7. A side member for a window screen comprising a portion to be attached to the sides of the window casing, a flange extending into the area to be screened, a cover portion hinged to said first named portion to swing between an open position and a closed position in which it is substantially in engagement with said flange, and means resiliently holding said cover portion in either of said positions.

8. A side member for attachment to the sides of a window casing and to retain the margins of a screen element, said member comprising a portion to be attached to said sides, a flange portion extending into the area to be screened, a cover portion hinged to said first named portion outwardly of said flange to swing between an open position and a closed position in which it is substantially in engagement with said flange to define therewith a chamber, a trip carried by said cover portion engageable by said margins when said cover portion is in its open position, as it is brought from the outside inwardly against said flange thereby to move said cover portion into its closed position and in said closed position, said trip being within said chamber.

9. The side member of claim 8 and means resiliently holding the cover portion in either its open or its closed position.
